TURBINE INSTALLATION

Application filed November 6, 1930, Serial No. 493,743, and in Germany December 3, 1929.

In some turbine installations, three or more turbines deliver their power through separate pinions to a single reduction toothed wheel gear driving the propeller shaft. When there are, for example, four turbines, two pinions with their driving turbines are located on opposite sides of the wheel in, or in the neighborhood of, the mid plane of the wheel, while the third and fourth turbines have to be mounted above the first two. It is usual to support all of the turbines primarily on the gear casing, either in recesses or on brackets, the free ends of the turbines being supported on cast or forged foundations. This arrangement has the disadvantage that if it is necessary to dismount the casing of the large wheel, the connection between this casing and the turbine casings must be released to enable the upper part of the gear casing to be lifted. In doing this, it is necessary to change the positions of the turbine rotors, which positions had previously been established with considerable care. In reassembling the parts, the rotors must be realigned which involves considerable time and expense.

The main object of my invention is to avoid these disadvantages. I accomplish this by providing one or more separate carriers in front of the gear casing, and fixedly secured to the lower stationary part of the gearing casing, and detachably secured to the upper removable part. The casings of the upper turbines are supported at one end by these separate carriers, while at the other end, three turbines are supported by a corresponding foundation block.

With this arrangement, to dismount the upper part of the gear casing, it is merely necessary to detach the end connection between it and the said separate carriers for the turbines, and to disconnect the couplings between the turbines and the pinion shafts. The support of the turbine shafts remains undisturbed.

Certain examples embodying the invention are illustrated in the accompanying drawing:

Fig. 1 is a side view of one form embodying the invention certain parts of the casing

being shown detached in solid lines and in position in dotted lines.

Fig. 2 is a vertical section through the removable gear casing shown in Fig. 1.

Fig. 3 is an end view of Fig. 1, and showing a three turbine arrangement, the upper turbine and the shafts of the lower turbines being shown in section.

Fig. 4 is a view similar to Fig. 3 but showing four turbines.

Fig. 5 is an end view of Fig. 6, and

Fig. 6 is a view of the form shown in Fig. 5, but with certain of the parts in spaced relationship.

In the construction shown in Figs. 1 and 2, there is a main shaft *s* which may be a marine propeller shaft, and which is driven by three turbines. The two side turbines are not shown, but are connected to the two side shafts *r* and *t*. An upper turbine *d* is connected to the shaft *v*. A reduction gearing is provided between said shafts *r*, *t* and *v*, and said main shaft *s*. This includes a large gear wheel *k* mounted on the shaft *s*, and meshing with pinions *l*, *m* and *n* on the shafts *r*, *t* and *v* respectively. The gearing casing is formed of two sections *a* and *a'* uniting along a horizontal dividing plane *X* passing through the axis of the shaft *s*.

The turbines are in alignment with their respective shafts *r*, *t* and *v*, and are coupled thereto.

As an important feature of the present invention, a support *b* is provided, the bottom end of which is fixed to the lower stationary section of the gear casing *a*, and the upper portion is detachably secured to the upper section *a'*, and serves to support one end of the casing of the turbine *d*. The other end of said turbine casing may be supported by any suitable means, as for instance a foundation block *h*. For detachably securing the upper section *a'* to the support *b*, a coupling piece *c* is provided which is secured between said section and said support by any suitable means, as for instance bolts *c'*. Enclosing the couplings *e* are separable casing sections *e'*.

When it is desired to remove the upper gear casing section *a'* to permit repairing or in-

spection of the interior of the gear casing, the shaft coupling casing *e'* is removed, the couplings *e* unfastened, and the bolt or bolts *c'* which secure the coupling piece *c* to said upper section, are removed. The casing *a'* may then be lifted without interfering with the support of the turbine casing *d*, and without affecting the setting of the turbine shaft.

In Fig. 4 is shown a construction in which 10 two upper turbines *d'* are provided above the dividing plane *X*, these turbines serving to drive the two shafts *w* which have the two pinions *n'* which mesh with the large gear *k*. In this construction, the support *b'* may 15 be suitably widened in order to support the turbines *d'*, or if desired, two separate supports may be provided for supporting the separate turbines *d'*. In this arrangement the upper section *a'* may be removed in a 20 manner similar to that already described with reference to Figs. 1 and 2.

In Figs. 5 and 6, two low pressure turbines *f* drive shafts *p* having pinions *o* meshing with the large gear wheel *k* near the top 25 thereof. Two high and intermediate pressure turbines *g* are disposed below the turbines *f*, and have their shafts *y* provided with pinions *l'* and *m'* also meshing with the large gear *k*, and being advantageously disposed 30 below the axis of the shaft *s*. The upper turbines *f* may be supported on one or more supports *b''* in a manner already described, and may rest on one or more foundation blocks *h* at the other end of said turbine.

35 The dismounting of the upper section *a'* of the gear casing is effected in the same manner as already described with reference to the constructions of Figs. 1, 2 and 3. The lower turbines *g* may be rigidly connected 40 directly to the lower section of the gearing casing as shown in Fig. 5, and have the casings thereof preferably divided along planes *i* inclined in the horizontal in order to permit the upper portions of these casings to be 45 removed from underneath the turbine casings *f*.

What I claim is:—

1. In a turbine installation, a shaft, a turbine, reduction gearing between said shaft and said turbine, a casing for said gearing, said casing being divided into an upper section and a lower section, a support member connected to the lower section of said gear casing, and adapted to support one end of said turbine, and means detachably connecting said support to the upper section of said gear casing.

2. In a turbine installation, a shaft, a turbine, reduction gearing between said shaft and said turbine, and having a casing divided into an upper section and a lower section, a support member connected to the lower section of said gear casing, and adapted 65 to support one end of said turbine, and sepa-

rate means for supporting the opposite end of said turbine.

3. A turbine installation including a shaft, a turbine mounted above said shaft, reduction gearing disposed between said shaft and 70 said turbine, a casing for said reduction gearing, said casing being divided into an upper and a lower section, a pair of turbines mounted on opposite sides of said shaft and disposed below said first mentioned turbine, the 75 casings of said lower turbines being divided in planes inclined to the horizontal at such an angle as to enable the upper sections of said lower turbines to be dismounted and removed from beneath said upper turbine. 80

4. A turbine installation including a shaft, a pair of turbines mounted above said shaft, reduction gearing disposed between said shaft and said turbines, a casing for said reduction gearing, said casing being divided into an upper and a lower section, a pair of turbines mounted on opposite sides of said shaft, and disposed below said first mentioned turbines, the casings of said lower turbines being divided in planes inclined to 90 the horizontal at such an angle as to enable the upper sections of said lower turbines to be dismounted and removed from beneath said upper turbines, a support member connected to the lower section of said gear casing and adapted to support one end of one of said first mentioned turbines, and means for detachably connecting said support to the upper section of said gear casing.

In testimony whereof, I have signed my 100 name to this specification.

DR. GUSTAV BAUER.
